(57) **CLAIM**

The ornamental design for a key guard cabinet handle, as shown and described.

DESCRIPTION

FIG. 1 is a top front perspective view of a key guard cabinet handle showing my new design.

FIG. 2 is an inverted bottom rear perspective view thereof.

FIG. 3 is a rear elevational view thereof.

FIG. 4 is a left side elevational view thereof.

FIG. 5 is an inverted front elevational view thereof.

FIG. 6 is a front elevational view thereof.

FIG. 7 is a top plan view thereof; and,

FIG. 8 is a right side elevational view thereof.

The broken lines of a cabinet drawer showing are for illustrative purposes and form no part of the claimed design.
